UNITED STATES PATENT OFFICE.

GEORGE HENRY BRYANT, BENJAMIN BERTIE JOHNSON, AND RICHARD GRANT VAN-NECK, OF LONDON, ENGLAND, ASSIGNEES TO THE RELAY AUTOMATIC TELEPHONE COMPANY, LIMITED, OF LONDON, ENGLAND.

PARTY-LINE TELEPHONE.

Application filed June 17, 1924, Serial No. 720,574, and in Great Britain June 26, 1923.

Our invention relates to improvements in lock-out party lines and has for its object to provide a cheap, simple and reliable party line apparatus.

5 Our invention especially relates to that type of system in which the subscribers' lines are commoned to a single junction at a small local exchange and in which local connections are performed by automatic apparatus controlled by an operator at the other end of a junction to a distant or main exchange, while distant or interoffice connections are completed by the operator in the usual manner. Such small exchanges are 10 frequently termed "village" exchanges.

According to our invention we provide party line apparatus whereby (a) any party to the line can obtain access to the line, to the exclusion of all others, provided of course 20 that the line is idle, (b) an operator can call any party and cause the connection of his station to the line to the exclusion of all others even though a conversation between two of the parties to the line is in progress, (c) a party wishing to talk to any other party on the same line can without rendering the line accessible to any third party who may attempt to originate a call render the line 30 accessible to another whom the operator may be selecting, (d) a station which may be falsely in a calling condition can be disabled from interfering with the operation of the line, (e) upon a call being attempted for any such disabled station a distinctive signal 35 can be given.

A preferred method of carrying our invention into effect is to provide at some convenient point, such as at a small local exchange, a number of connecting relays, one 40 for each station, for connecting the stations to the party line. These relays would be controlled by the line relays of the stations or by a selective device (such as a relay recorder) actuated by the operator at the main 45 exchange. A cut-off relay would be provided for the usual purpose of cutting out the line relay, and a fault relay may be provided for preventing a false calling condition from interfering with the effective operation of 50 the line. Relays would be provided for per-

mitting the stations to control the clear-down of a connection until the operator shall have taken control of the connection and for thereafter transferring to her the control of the clear-down. The relays may assist in 55 passing supervisory signals from the stations to the main exchange and for "tripping" the ringing signal when a wanted party answers.

Our invention will now be described in detail as applied to such a semi-automatic 60 party line system in which relays only are used but it will be obvious to those skilled in the art that the system may work equally well with other apparatus having normally adjacent contacts.

65 Of the accompanying drawings, Figure 1 shows two of the party subscribers' lines S^1 and S^2 connected to a common line L .

Figure 2 shows a current feeding group ABF common to all the subscribers whose 70 lines can be connected to line L . To the right of the feed is shown part of the junction J leading to the main exchange.

Figure 3 shows the incoming end of the junction at the main exchange, terminating 75 in an operator's position.

Figure 4 shows a known dialling cord.

Figure 5 shows a modification of a well known relay recorder.

To initiate a call a subscriber S^1 lifts his 80 receiver and is immediately connected to the junction J via the feed. An ordinary calling lamp CL calls the attention of the operator who thereupon inserts the answering plug of her cord circuit and enquires for the connection desired.

If the connection desired is other than a local one, it is completed in the usual manner.

If the connection desired is a local one, 90 the operator asks the calling subscriber to replace his receiver. The subscriber hanging up will cause a "clear" signal to be given to the operator to show her that he has done as requested. This act does not result in the 95 release of the calling subscriber's line from the junction, the connection being held as long as the operator has the answering plug in the jack.

The operator thereupon inserts the dial- 100

ling plug DP into the dialling jack DJ and dials the required number. The dialled impulses are received by the recorder which, upon receipt of the complete train, marks the wanted subscriber. The operator then withdraws the dialling plug and inserts the calling plug of the cord circuit and rings the wanted subscriber in any convenient manner.

18 Both the called and calling subscriber are rung. Upon the called subscriber answering the other bell will stop ringing thus informing the called party that the other party has answered. Conversation may now take place.

19 The circuit operations will now be described in detail.

20 A subscriber S¹, Figure 1, upon lifting his receiver closes an energizing circuit 2 for relay LE which in operating closes circuit 3 for relays JNC and TCD. Relay JNC operating closes circuit 4 round the calling subscriber's line in which relay A¹ energizes. Relay A¹ operates and closes circuit 5 in which is included relay AIX. Relay AIX in operating closes circuit 6 for relay G to energize. This circuit was prepared by TCD.

21 It has been assumed that the junction J was free as otherwise G would have been operated and circuit 3 open, so that JNC would not have had an energizing circuit.

22 G in energizing completes energizing circuit 8 for relay CO and also breaks the test wire T, thus breaking circuit 3. JNC is now holding only over the holding circuit 8 and TCD over the following circuit:—Battery, winding of relay TCD, contacts B¹—3¹, TCD—3¹, G—8, earth 8. In circuit 8 relay CO energizes and closes a circuit for relay F. It also opens circuit 2 so that LE de-energizes. When AIX operated it completed circuit 7 from earth, Figure 3, and the operator's line relay OL operates in series with impedance B², Figure 2. Relay OL closes a lighting circuit for the operator's calling lamp CL.

23 Upon the operator answering the call, which she does in the usual manner by inserting the answering plug of her cord circuit into the answering jack A, relay B¹, Figure 2, operates over circuit 9 which terminates in battery in her cord circuit, which circuit is not shown as it is a well known arrangement.

24 Relay B¹ energizing breaks the holding circuit just described of TCD at contact B¹—3 and also completes an alternative holding circuit 6¹ for G.

25 Relay G is now under the control of the operator and the subscriber cannot release the connection between himself and the junction until the plug is withdrawn from the jack.

26 It will now be seen that should another

subscriber on the same party line attempt to initiate a call his relay JNC will not be able to energize because its energizing circuit will be broken at contact G—3. Further as his relay JNC will not energize he cannot overhear the conversation.

27 To return to subscriber S¹ he informs the operator the required number and if that number be other than a local number the call is put through in the usual known manner. Suppose, however, the required number be in the same local exchange, the operator asks the calling subscriber to hang up his receiver. Such action breaks the loop circuit 4, thus causing A¹ to de-energize. A¹ de-energizing releases circuit 5, causing AIX to de-energize. AIX de-energizing breaks circuit 9, thus releasing B¹, but at the same time an energizing circuit is completed for relay I which energizes and maintains a holding circuit 6² for G. Thus the subscriber's connection with the junction J is not released.

28 Battery 7 no longer being fed through relay B² to the A junction wire, the supervisory lamp in the operator's cord circuit lights in the usual manner, informing her that the subscriber has hung up. She now inserts her dialling plug DP, Figure 4, into the dialling jack DJ, Figure 3, thus completing circuit 10. In this circuit are included relay FIP, Figure 4, and relay DJC, Figure 3, which energize. The latter relay transfers the junction J from the answering jack leads to those of the dialling jack.

29 Battery is thus fed to both the junction wires over circuits 11 and 12, from common negative 11, Figure 3. Circuit 12 passes through relay RP, Figure 2, which energizes and locks over its own contacts and the junction.

30 Relay NUC, Figure 2, now has an energizing circuit over the upper make contacts of RP. Relay NUC energizes and holds in a circuit which includes contacts of relays SOX and G.

31 Relay RP energizing closes circuits 13 and 14. In circuit 13 relay DC1, Figure 5, energizes. In circuit 14 and its off shoot circuits 14^a, 14^b, 14^c, 14^d, 14^e relays B5.0, B4.9, B3.8, B2.7, B1.6, energize. These relays in energizing prepare circuit 15 at present open at contacts I—15. Circuit 15 finishes at a heavy broken line on which is battery put on by relay RP. This line will herein-after be referred to as battery RP.

32 The recorder is now prepared and impulses from the operator's dial are received over the B junction wire only by relay I, Figure 2. Although relay RP holds over the junction it does not receive impulses as battery is fed to it continuously over the A junction wire from battery 11, Figure 3.

33 For the purposes of this example it will be supposed that three impulses are sent.

When the B junction wire is broken for the first time relay I de-energizes and completes circuit 15. M1.6 energizes and holds over its own contacts *a* to earth through winding of DC2, which energizes and transfers slow release relay DC1 to the impulse wire IW.

5 B1.6 is also transferred to the impulse wire via circuit 15 as far as the contacts of B1.6 thence over contacts 15¹, winding of B1.6, circuit 14 to battery RP.

At the end of the impulse, when relay I energizes again, B1.6 de-energizes.

At the second break of the B junction wire relay I de-energizes M2.7 energizes over the following circuit:—Circuit 15 as far as contacts B2.7—15, thence via contacts B1.6—16, M2.7—16, B3.8—16, relay M2.7 to battery RP.

20 M2.7 energizes and holds over its own contacts and outer make contacts of B3.8.

B2.7 is now transferred to impulse wire IW circuit 15 as far as the contacts of B2.7 thence over contacts B1.6—16, M2.7—15^b, winding of B2.7 circuit 14 to battery RP.

25 At the end of the impulse, when I energizes again, B2.7 de-energizes and breaks the holding circuit of M1.6 which de-energizes and re-closes circuits 14 and 14^a; relay B1.6 energizes again in these two circuits.

At the third break of the B junction wire, I de-energizes and relay M3.8 is energized over the following circuit:—Circuit 15 as far as contacts B3.8—15, thence via B2.7—17, M3.8—17, B4.9—17, relay M3.8, to battery RP.

M3.8 energizes and holds over its own contacts and outer make contacts of B4.9.

40 B3.8 is now transferred to the impulse wire IW, circuit 15, as far as the contacts of B3.8, thence over contacts 15^c, winding of B3.8, circuit 14 to battery RP.

At the end of the impulse, when I energizes again, B3.8 de-energizes and breaks the holding circuit of M1.6, which de-energizes and re-closes circuit 14 and 14^a; relay B2.7 energizes again in these circuits.

45 As no more impulses are sent relay I remains energized and circuit 15 remains broken for a considerable period. DC1 now de-energizes having no holding circuit and completes circuit 18 marking subscriber S3 by energizing relay JNC3. Relay JNC3 energizes and holds over its own contacts over a circuit from battery, relay CO3 to earth over make contacts of G. CO3 energizes and in turn energizes F3. SO which also energized in circuit 18 operated SOX over circuit 19. SOX holds over its own make contacts and breaks the holding circuit of NUC.

50 The operator now withdraws her dialling plug, which causes RP to release, this in turn releasing the recorder. She then in-

serts the calling plug into the calling jack CJ and sends out ringing current over the A junction line in any known manner. I is kept energized by the negative return on the B line.

70 The bells of both the calling and called subscribers are now rung.

As soon as one or other of the subscribers answers the loop is again closed and A¹ operates over circuit 4. AIX also operates in 75 circuit 5, cutting out I and putting B¹ and coil B² back into circuit again.

At the end of the conversation as both the subscribers hang up their receivers A¹ de-energizes and consequently AIX also de- 80 energizes.

The supervisory lamp in the cord circuit lights in the usual known manner and the operator takes down the connection thus releasing B¹. G now having no holding circuit releases and breaks the holding circuit 85 which releases JNC, JNC3, CO and CO.3.

The feed and junction are thus released and the whole system returned to normal.

For incoming calls from other exchanges 90 for one of the party lines, the operator inserts her dialling plug, thereby completing circuit 11 in which I energizes. I completes a circuit for G, which energizes and in turn completes circuit 12 for RP.

95 The recorder is prepared as before and G holds over the upper contacts of RP while I is impulsing.

The operator then dials and the wanted subscriber is marked as before. She then 100 inserts her calling plug and rings the wanted subscriber who upon answering energizes A¹ which in causes AIX to energize and cut out I and RP.

Should an important incoming call for 105 one of the party line subscribers come in while the junction is in use, the operator may force the release by withdrawing the plugs of the cord circuit and then inserting the dialling plug. G will then be released. 110 The loop of the subscriber's circuit being closed when JNC and CO de-energize, LE will immediately energize. Thus F will hold so that circuit 3 will not be closed. JNC cannot operate. The operator may 115 now proceed to call the wanted subscriber in the manner already described.

Should a subscriber's line be out-of-order, that is, on his fault relay, his marking wire will be broken and consequently, when he is marked, circuit 18 will not be completed, being open at contacts of F. The circuit of NUC will not be broken by SOX energizing and when the operator withdraws her dialling plug and substitutes the calling plug, 120 relay RP will release. The release of RP and the energized condition of SOX and energized condition of NUC complete a circuit for buzzer NU. (This buzzer has two 125 windings and is energized by current in one 130

winding and de-energized upon operation when current flows in both windings). This buzzer can be heard over the junction by the operator or by a calling subscriber.

- 5 FA is a supervisory relay through the winding of which under abnormal conditions the current for certain of the relays is drawn. The relays which may draw their current through this relay are indicated by 10 an asterisk. An abnormal condition is any condition which causes these relays to draw current when G is not operated.

If G is operated the winding of FA is short-circuited so that these relays draw 15 current direct. If current is drawn through the winding of FA this relay operates and connects negative to one of the wires of the junction and gives a calling condition. This calling condition can also be given if the 20 fuses which supply battery to the various parts of the exchange should blow. These fuses may be of the lead type and are indicated in the drawing by Z.

We claim:—

- 25 1. A telephone system comprising a main exchange and a sub-centre between which a two wire junction extends, a plurality of two wire subscribers' lines terminating at said sub-centre and normally disconnected from 30 the junction, connecting means at the sub-centre for connecting any one of the subscribers' lines to the junction when such line is a calling line, said connecting means being adapted to be controlled from the main exchange for connecting another subscriber's 35 line to the junction even though the junction be engaged.
2. A telephone system comprising a plurality of subscribers' lines and a junction 40 from a main exchange over which junction any of the subscribers' lines can call the said main exchange and over which the main exchange can select and call any of the subscribers' lines, said subscriber's lines being 45 normally disconnected from said junction, characterized in that the junction is provided with connecting relays equal in number to the number of subscribers' lines and with an impulse counting selecting device by 50 which any of the said relays can be selected

and operated to connect the junction to the line to which said relay belongs.

3. A telephone system according to claim 1 in which the junction is provided with a number of sets of contacts, one set for each 55 line, and in which each line is provided with a set of contacts normally adjacent to the set appropriate to its line but belonging to the junction.

4. A telephone system comprising a main 60 exchange and a sub-centre between which a two wire junction extends, a plurality of two wire subscribers' lines terminating at said sub-centre and normally disconnected from the junction, connecting means at the 65 sub-centre for connecting any one of the subscribers' lines to the junction when such line is a calling line, selecting means whereby an operator at the main exchange may select and cause the connecting of the junction of 70 a second line to the exclusion of all other lines except the one first connected thereto, and controlling means for maintaining in association with the junction the first line the said controlling means then being enabled for control by the operator to control 75 the selecting means.

5. A telephone system according to claim 4 in which means is provided whereby a line which falsely simulated a calling line may be 80 released from the junction and render it free for calls from other lines.

6. A telephone system according to claim 1, in which means is provided for signalling the main exchange when the apparatus at the 85 branch exchange becomes faulty.

7. A telephone system according to claim 1 in which means is provided for notifying the operator that a wanted line is unavailable, said means including circuit arrangements for notifying any other party who may be connected to the junction that a selected line is unavailable.

In testimony that we claim the foregoing as our invention, we have signed our names 95 this twenty third day of May 1924.

GEORGE HENRY BRYANT.
